CLAIM

The ornamental design for a display screen or portion
thereof with graphical user interface, as shown and
described.

DESCRIPTION

The patent file contains at least one drawing executed in
color. Copies of this patent with color drawings will be
provided by the Office upon request and payment of the
necessary fee.

The FIGURE is a front view of a display screen or portion
thereof with graphical user interface showing our new
design.

The outer perimeter illustrated by dashed broken lines in the
drawings illustrates a display screen or portion thereof and
forms no part of the claimed design.
